DETACHABLE SPOON FISHING LURE OR THE LIKE

Mathew A. Strumor, 27 Glenbrook Drive,
New Rochelle, N.Y. 10804

Filed June 1, 1966, Ser. No. 2,498

Term of patent 14 years

(Cl. D22—29)

FIG. 1

FIG. 2

FIG. 3

FIG. 5

FIG. 6

FIG. 4

FIG. 1 is a top plan view of a detachable spoon fishing lure embodying my new design;

FIG. 2 is a side elevational view thereof, the opposite side being identical;

FIG. 3 is a bottom plan view thereof;

FIG. 4 is a front elevational view thereof;

FIG. 5 is a rear elevational view thereof; and

FIG. 6 is a sectional detail view taken along the plane of line 6-6 in FIG. 2.

I claim:

The ornamental design for a detachable spoon fishing lure or the like, as shown and described.
